(57) **CLAIM**

The ornamental design for an electronic copying machine, as shown and described.

DESCRIPTION

FIG. 1 is a perspective view of the front, top and left side of an electronic copying machine showing my new design; FIG. 2 is a perspective view of the rear, top and right side thereof;

FIG. 3 is a front view thereof;

FIG. 4 is a top plan view thereof;

FIG. 5 is a right side view thereof;

FIG. 6 is a left side view thereof;

FIG. 7 is a rear view thereof;

FIG. 8 is a bottom view thereof; and,

FIG. 9 is a perspective view thereof with the tray being opened.

1 Claim, 9 Drawing Sheets

FIG. 1

*FIG. 2**FIG. 3**FIG. 4*FIG. 5

*FIG. 6*FIG. 7

FIG. 8

FIG. 9
